1

Among the known aiming devices for anti-aircraft weapons, experience shows that those have proved most successful which are provided with optical aiming devices, since such aiming contrivances can be constructed in such a manner that aiming point and target can be seen clearly with the same visual adjustment of the eyes. For the purpose of further improving such aiming devices it has been suggested to equip them with aids for the accurate determination of the flying plane of the target, i. e. the plane given by the gun position and the target course, assuming the latter to be a straight line.

In the known designs of such aids an aiming line appears in the field of vision of an optical aiming device which may for instance, consist of an aiming telescope, this aiming line being arranged turnably and parallel to the apparent aircraft course in such a manner that for the determination of the flying plane position the aiming line is geared to an arm arranged turnably around a constantly vertical axis, and that this arm, when set parallel to the flying plane, causes the aiming line visible in the field of vision of the aiming device also to be parallel to said plane.

The present invention relates to an aiming device which also makes use of optical aiming devices and aids such as described, an aiming line being arranged visibly in the field of vision of an aiming device and turnably for the purpose of setting it parallel to the apparent aircraft target. According to the invention an aiming point is arranged in the optical aiming device, which, with regard to the lateral movement of the weapon, is rigidly affixed to the latter, in such a manner that it can be shifted along the aiming line and turned with it; moreover, a triangle is provided for the reproduction of the aiming-off triangle in space, which is arranged turnably around one of its sides as axle and which transmits its rotation to the aiming line, it being in drive-connection both with the members intended to turn the weapon laterally and with a device for manual operation; moreover, that side of the reproduced triangle which, with its rotating axle, encloses the aiming-off angle resulting from its relations to the distance from, and the speed of, the target is connected via the driving members with the shiftable aiming point in such a manner that when the aiming-off angle is altered the aiming point is shifted correspondingly and thus the aiming-off angle is transmitted to the optical aiming device.

The invention presents a particular advantage

because the aiming device is rigidly connected to the weapon in respect of the latter's lateral movement; this fact procures a considerably more stable connection between aiming device and weapon than is the case with the known aiming devices described above in which the aiming device is arranged turnably in respect of the weapon, both with regard to side and to position.

It is advisable to use a so-called reflex sight 10 as aiming device in which the target is looked at through a glass plate, set obliquely to the sighting line and operating simultaneously as a mirror in such a manner that by means of a special source of light a hair cross or such-like is projected on 15 the glass plate and, by reflection, from the latter to the eye of the observer. This sight can easily be designed in such a manner that on the glass plate only the aiming line preferably consisting of two parallel lines arranged at a small distance 20 from each other and the aiming point, which can be shifted along the aiming line are visible without other parts, such as those necessary to shift and hold the aiming point, interfering with the field of vision.

25 In the attached drawing a specific embodiment of the present invention is explained and described.

Fig. 1 shows a side-view of a small-calibre gun with an aiming device suitably arranged on it;

Fig. 2 a view in perspective of the aiming device with cover removed, and

30 Figs. 3 and 4 show cross and longitudinal sections through the optical part of the aiming device, Fig. 3 being a section along line *s*—*s* in Fig. 4 while the upper half of Fig. 4 shows a section along line *t*—*t* and the lower half a section along line *v*—*v* in Fig. 3.

35 According to Fig. 1 upper gun carriage 2 is fastened to lower gun carriage 1 in such a manner that it can rotate around a vertical axle. On upper gun carriage 2, in addition to seat 6 for the operator, cradle 4 carrying weapon 3 is mounted in such a manner that it can be rotated around horizontal axle 5. By operating hand wheel 7 the whole upper gun carriage with cradle and weapon can be turned around the vertical axle, and in a similar fashion, by operating hand wheel 8, cradle 4 and with it weapon 3 can be turned in a vertical plane. To upper gun carriage 2, slightly to one side of the longitudinal axis of weapon 3, support 11 is rigidly affixed, while on both sides of cradle 4 one rod 12 each is connected articulately. The 40 upper ends of support 11 and of pair of rods 12

are jointed by plate 13 in such a manner that the latter is always parallel to the direction of the weapon, i. e. support 11, rods 12 and plate 13 form together a parallel guide. Besides plate 13 casing 14, which is supported against plate 13 by means of part 15, is hinged to the axle arranged at the end of support 11. From one of the two side walls of casing 14, which stand parallel to the weapon axis, reflex sight 16 protrudes as shown diagrammatically in Fig. 1.

Fig. 2 shows the design of the aiming device in detail. Support 11 is provided at its upper end with U-shaped part 20 whose arms 21 carry horizontal axle 22. To the ends of an axle 22 extending beyond the ends of arms 21, plate 13 is pivoted by means of extensions 23, while between arms 21 on axle 22 holders 24 are pivoted, by means of which casing 14 is supported against axle 22. As an additional bearing point for casing 14 on plate 13 part 25 is provided, protruding laterally, on which lies bolt 15 having an enlarged lower end, and which in a manner requiring further explanation, is held by the slide guide 27 affixed to the bottom of casing 14.

The reflex sight is affixed to the left side-wall of casing 14 as shown in Fig. 2. It consists in the main of glass plate 28, which can be turned around a gudgeon placed in part 29, and of socket 30 inserted in the side-wall of casing 14. Above the latter, holding plate 31 is affixed to casing 14, to which on the one hand bearing 29 and on the other hand support 32 are rigidly connected. At the bottom of casing 14 electric bulb 34 in socket 33 is arranged in the axis of socket 30, by means of which the reflection of two straight lines arranged at a small distance from the longitudinal axis of socket 30, in a plane vertical to this axis and turnably around it, is projected on to glass plate 28. The design of the parts arranged in socket 30 can be seen in detail in Figs. 3 and 4, and will be fully explained when these drawings are described.

For the rotation of the two lines forming the aiming line around the axis of socket 30 the following mechanism is provided: By a frame consisting of carriers 35 and 36 which is affixed to the upper and lower side-walls of casing 14 two horizontally arranged co-axial shafts 37, 38 are borne to the opposite ends of which U-shaped carrier 39 is affixed. At the outer end of shaft 38 drawn through the right-hand side-wall of the casing lever 40 is affixed, and a similar lever 41 is affixed to the outer end of shaft 22 in the same manner. By means of rod 42 which is pivoted to the ends of levers 40, 41 the latter are always kept parallel to each other, independent of the swivel movements of casing 14 around shaft 22 which is arranged in arms 21 in such a manner that it cannot be turned. In consequence the plane formed by U-shaped carrier 39 always maintains its direction in space during said swivel movements, the vertical being chosen as this direction.

In a socket 43 affixed to the horizontal traverse of carrier 39 hollow shaft 44 is arranged which bears at its upper end disc wheel 45 and at its lower end bevel gear 46. For the purpose of turning wheel 45 around its constantly vertical axis its underside is provided with a toothed rim engaged by bevel gears 47 which in its turn is geared to the pair of spur-wheels 48. The upper wheel of this pair, together with a bevel gear pertaining to the pair of bevel gears 49, is rigidly affixed to a hollow shaft borne by shaft 38. By means of the pair of bevel gears 49 this hollow shaft is geared to shaft 52 which pierces the

lower side-wall of casing 14 and is borne by guide piece 51, the end of this shaft protruding from casing 14 being itself geared to hollow shaft 54 via a further pair of bevel gears 53. Hollow shaft 54 forms part of compensation gear 55 which is not depicted in detail but which is affixed to part 20 by means of support 56. Shafts 57 and 58 also engage with compensation gear 55, shaft 57 being provided with hand crank 59 while shaft 58, being hollow, is also borne turnably by shaft 22 and carries at one end one of the wheels of the pair of bevel gear wheels 60. The second wheel of this pair is mounted upon a shaft 61 which is carried in a support 11; the shaft 61 is operatively connected with the hand crank 7 (Fig. 1) for the lateral movement of the gun by a gear drive which is not shown in the drawings.

Disc wheel 45 is thus driven from two different places. The transmission ratio of the gear drives 20 including the compensation gear 55 which transmits the rotation of the hand crank 7 (Fig. 1) to the disc wheel 45, is so selected that the rotation of the disc wheel 45 produced by this crank 25 is equal to the lateral rotation of the gun but takes place in the opposite direction.

Rack 65, arranged slideably between two guide rods 66 which are rigidly affixed to disc wheel 45, bears at its end universal joint 67 through which link 68 is connected to rack 65 in such a manner that it can be turned both around the vertical axis of the latter and around an axis in a normal position to the vertical axis. The other end of link 68 is slideably mounted in socket 69, the latter being arranged in such a manner that it can be turned around axle 71 rigidly affixed to it and borne by a U-shaped intermediary piece 70. Intermediary piece 70 is affixed to shaft 72 whose one end is journaled in a carrier 73 affixed to frame 35, 36, the other end bearing hollow shaft 74 which is journaled in a carrier 36 of the frame. Of pair of bevel gear wheels 75 one wheel is borne by axle 71, which is rigidly connected to socket 69, while the other wheel is affixed to the end of hollow shaft 74. As can be seen on the drawing, the center axis of shaft 72 is parallel to carriers 35 of the frame, and thus participates in the swinging movements of the frame 14 about the shaft 22. Furthermore, the axis of the shaft 72 intersects the centre axis of shafts 37, 38 at the same point at which the centre axis of universal joint 67, parallel to the rack, also intersects the centre axis of shafts 37, 38.

On support 73 and on carrier 35 of the frame 55 two further shafts 76, 77 are arranged which, via pairs of bevel gears 78, 79 are geared to shaft 72, and hollow shaft 74. Shafts 76 and 77 carry spur wheels 80, 81, which work together with corresponding wheels arranged in socket 30.

The mechanism described functions as follows on condition that rack 65 does not slide on disc wheel 45: If only the hand crank 59 is turned, i. e. if the gun does not alter its setting either in respect of the side angle or the angle of sight 65 casing 14 also remains stationary in space while the disc wheel rotates around its vertical axis, simultaneously moving rack 65. The point of intersection of the longitudinal axis of lever 68 with axle 71 forms the apex of a cone the axis of which is formed by the center axis of shaft 72, and which is inclined to the horizontal plane of the disc wheel 45 at an angle which is substantially the same as the elevation of the gun. The link 68 moves along the mantle surface of this cone during the rotation of the disc 45.

The rotary movement transmitted to intermediary piece 70 by link 68 is not only transferred to shaft 72 but, owing to the rotation of axle 71 around shaft 72, also to hollow shaft 74. In view of the fact that the cone axis is, as a rule, oblique to its base, formed by disc wheel 45, the angle between link 68 and the centre axis of shaft 72 alters constantly during rotation, a fact which expresses itself, moreover, in the rotation of bevel gear wheel 75 borne by shaft 71 around its own axis. A further consequence is that the two shafts 72 and 74 do not rotate synchronously in the course of a half turn of disc wheel 45, but assure an increasing and then decreasing advance in relation to each other. If instead of hand crank 59 hand crank 7 (Fig. 1) is operated, casing 14 rotates together with the gun, disc wheel 45, however, receiving an additional rotary movement in the opposite direction as described in such a manner that rack 66 always runs parallel to itself. The relative movement of disc wheel 45 and link 68 in relation to axle 72 is analogous to the motion described above.

In Figs. 3 and 4 the design of the optical part of the aiming device is depicted. Socket 30 is affixed to one of the side-walls of casing 14 by flange 85, so that the part of socket 30 which is on the right side of this flange in Fig. 4 is situated inside casing 14. In this part of the socket there are two annular bearers 86 and 87 which, by means of ball bearings, are arranged in such a manner that they can be turned around the longitudinal axis of socket 30. On their circumferences they are each provided with a toothed rim which is engaged by spur-wheels 80, 81 respectively. A holder of bearer 86 holds reticule 88 whose even back surface is covered with a non-transparent layer 88' with the exception of two thin straight lines 89 running parallel to each other at a small distance from the axis of socket 30. At bearer 86, moreover, two plates 90 are affixed directly behind reticule 88 by means of screws 91 in such a manner that they run parallel to the two lines 89 at some distance from the centre axis of socket 30. Both plates, by means of separation pieces 92, are held at such a distance from each other that the two rollers 93, 94 and steel tape 95 resting on them can be accommodated between them. Each of the two rollers 93 and 94 is rotatably mounted upon bolts 100 and 104, respectively; as will be described in greater detail hereinafter, the bolt 100 is movable in slots 107, in two plates 90, while the bolt 104 is firmly mounted in these plates. The ends of the tape 95 are affixed to two pins 96 which in their turn are rigidly affixed to carrier 87; furthermore, steel tape 95 carries on that part which runs parallel to lines 89 a small plate 98 which is affixed to said part by screw 97 and guided by two grooves in plates 90, the small plate being provided with pin 99 of such a length that it extends beyond the two lines 89. If bearer 87 is turned in relation to bearer 86 the two pins 96 move from the position shown in Fig. 3 to the left or to the right taking tape 95 with them, so that pin 99 shifts along the two lines 89. As in the course of this motion the tape lengths between pins 96 and the resting points on rollers 93, 94 do not vary in the same manner, roller 93 can be shifted between plates 90; it stands, moreover, under the tension of a spring. For this purpose the two plates 90 are provided with two longitudinal slots each in which the two bolts 100 and 101 can be shifted, bolt 100 bearing roller 93 while bolt 101 is pulled by a

spiral spring 103 affixed to plates 90. Outside plates 90 the two bolts are connected to each other by two connection pieces 102, so that any shifting of roller 93 outwards effects simultaneous shifting of bolt 101 and the overcoming of the spring pressure.

In the end of socket 30 shown on the right-hand side in Fig. 4 is placed condenser 105 by means of which the light coming from bulb 34 (Fig. 2) is projected on to lines 89 left transparent on reticule 88. From these the light rays fall on lens system 106 which is arranged in that part of socket 30 which protrudes from casing 14 in such a manner that its focus place coincides with surface 89 of reticule 88 provided with the two transparent straight lines 89. Owing to this fact an operator sighting across glass plate 28 and having accommodated his eye to "infinite" obtains a sharp picture both of lines 89 and of the target.

As can easily be gathered from Fig. 3, there exists between the shifting of pin 99 and the turning of bearers 86, 87 causing it, a relation which is not linear along the entire adjustment range of pin 99, this being due to the fact that the tape lengths between pins 96 and the resting points on rollers 93, 94 decrease in the same proportion as bearers 86, 87 are increasingly turned with respect to each other. This design allows the construction of lens system 106 to be considerably simplified, certain distortions of the reflections being admitted and corrected again by this non-linear relation between the reciprocal turning against of bearers 86, 87 and the shifting of pin 99. These simplifications are particularly valuable if the lens, for the purpose of obtaining a large field of vision, as is essential when dealing with rapidly moving targets, is provided with a big aperture angle.

Pin 99 serves the gunner as aiming point, when he looks through the reflex sight while firing at a target. The reflection of pin 99 visible on glass plate 28 (Fig. 2) must thus lie in the aiming line running through the eye of the gunner and the aircraft. The direction of the gun is for two known main reasons different from said direction. One reason is the speed of the aircraft, which moves a certain distance during the trajectory time of the shell, the other, that the shell does not move in a straight line but in a curve lying in a vertical plane. To obtain a hit the aiming line must form a first angle with the axis of the gun which lies in a plane comprising the gun position and the line of flight of the target, and which hereinafter is termed the flying plane—*the aiming-off angle*—and a second angle lying in a vertical plane—the superelevation angle. For the purpose of setting these two angles the aiming device is designed as follows:

In the side-wall of casing 14 shown on the right hand of Fig. 2 and in one of the two carriers 35 parallel shafts 110 and 111 are rotatably arranged. Outside casing 14 shaft 110 bears hand crank 112 and indicator 113 which turns over dial 114; furthermore, on shaft 110 screw 115 and endless worm 116 are arranged, the former carrying nut 117 while the latter works together with worm-wheel 118.

The scale 114 is provided with markings which make it possible to set the indicator 113 to a measured or estimated value of the distance of the airplane being shot at from the location of the gun. The rotation of the shaft 110 which is produced thereby causes the introduction of the value of this distance on the form of an angle

of rotation into the sight. It is then transmitted to the nut 117 on the one hand for the purpose of adjusting the above-mentioned superelevation angle and, on the other hand, to the worm 118 for the purpose of adjusting the above-mentioned aiming-off angle.

The setting of the superelevation angle which depends upon the distance of the target and also upon the elevation of the sighting line, directed from the weapon to the target, is as follows: The cam 119 is keyed upon the shaft 111 in such a manner that it rotates along with the shaft but is shifted longitudinally thereon. The cam 119 rests upon a roller 123 which is rotatably mounted upon the upper end of a bolt 15. The bolt 15 has a wider end supported in the above-described manner upon a shoulder 25 provided in the plate 13. The bolt 15 is movable in a guide piece 27 in a direction at right angles to the bottom of the casing 14. The cam 119 is provided with an annular groove which is engaged by a projection of the nut 117 for the purpose of facilitating the movement of the cam 119 along the shaft 111. When the nut 117 is shifted along the screw 115 by the rotation of the hand crank 112, the cam 119 is shifted upon the shaft 111 by a corresponding amount. A leverage 120, 121, 122 is provided for the purpose of rotating the cam 119 about the axis of the shaft 111. The two levers 120, 122 are arranged parallel to each other and are firmly fixed upon the shafts 111 and 38, respectively; the free ends of these levers are connected by the link 121. As already described, the levers 40 and 41 maintain their position in space in all swinging movements of the casing 14 or of the plate 13 about the fixed shaft 22; the same is equally true for the levers 120 and 122. However, the last-mentioned levers carry out a rotation about the casing 14, the amount of which is equal to the swinging movement of the casing 14 about the shaft 22. Consequently, each change in the elevation of the sight is transformed in a corresponding rotation of the cam 119 about the axis of the shaft 111.

The shaft 22 is located above the plane of the plate 13, since the ends 23 thereof are bent upwardly. Consequently, the rear ends of the holders 24 carrying the casing 14, which are mounted upon the shaft 22, are located above the plane of the plate 13, while the front end of the casing in its lowermost position is practically located upon the plate 13. The bottom of the casing 14 which is parallel to the optical axis of the reflex sight is thus located in a position which corresponds to the largest distance from the target and is thus less strongly inclined than the surface of the plate 13 by the extent of the superelevation angle, the surface of the plate 13 being parallel to the axis of the barrel.

The cam 119 is of such form that when the target is a short distance away it engages the roller 123 with its greater radius, while the shortest radius is in that position when the target is far away. In the first-mentioned instance the bottom of the casing 14 is practically parallel to the axis of the weapon.

The aiming-off angle is obtained in the usual manner by reproducing the aiming-off triangle lying in the flying plane, the side of the reproduced triangle corresponding to the distance from gun to target being kept constant. The side in the reproduced triangle which corresponds to the aiming-off distance is obtained by multiplying the target speed with a time value which depends upon the firing range of the ammunition used

and which is proportional to the reciprocal value of the average shell velocity. This value is only changed depending upon the distance of the predetermined intersection point and, therefore, it can be calculated as well from the determinable distance of the target which forms the traveling measuring point without any substantial error.

The corners of the reproduced triangle are formed by the turning point of socket 69 around axle 71, universal joint 67 and the intersection of axis of shaft 44 with the rotating axis of joint 61 running parallel to toothed bar 65. The distance of said intersection point from the joint of socket 69 corresponds to the invariable triangle side which always runs parallel to the optical axis of the reflex sight. Said time value is obtained by setting hand crank 112 on the measuring point distance obtained, cam 127 being correspondingly adjusted via worm-gear 116, 118 and shaft 126. This setting is translated to slide 128 of a multiplication gear, slide 128 being constantly pressed against cam 127 by a spring not shown. The multiplication gear includes the members 128 to 132 and is constructed as follows:

Slide 128, which can be shifted between two rails 129 affixed to the bottom of casing 14, displaces a lever 130 hinged to it, when it moves. The latter is provided with slots on both sides which are engaged by pins, one of which is affixed to nut 131 and the other to rail 132. Nut 131 can be shifted on screw spindle 133, the direction of the latter being at right angles to the direction in which the slide 128 is shifted. The shaft 135 to one end of which the hand crank 125 is secured, transmits its rotation through the bevel gears 134 to the spindle 133. The shaft 135 also carries an indicator 136 which can be adjusted over dial 137 arranged to set the aircraft speed. The extent of movement z which is transmitted by the lever 130 to the rail 132 is a function of the extent of movement x of the slide 128 calculated from any desired point of origin, and of the extent of movement y of the nut 131 which is determined from that position of the lever 130 in which this lever is parallel to the direction of movement of the slide 128. This function has the following mathematical formula:

$$Z = y \cdot \frac{b-x}{a+x}$$

In this formula, the constant a represents the distance of the above original point from the nut 131, while the constant b represents the distance of this initial point from the rail 132. When the values of x are small, this function is practically a straight line so that the shifting of the slide 128 is proportional to the product, $x \cdot y$. The cam disc 127 is so formed that its transmits the reciprocal value of the corresponding average shell velocity to the slide 128 for each value of the target distance set by the crank 112. Rail 132 which can be shifted in a direction at right angles to the sliding direction of slide 128 and which at its end forms a rack transmits its movement representing the value produced by the multiplication gear via gear 138, shaft 139 and the pair of bevel gears 140 to hollow shaft 141 resting on shaft 37. Hollow shaft 141, via a further pair of bevel gears, drives one shaft of differential gear 142 affixed to carrier 39, result shaft 143 of differential gear 142 being geared via a pair of bevel gears to one of the driving shafts of a further differential gear 145. The two differential gears' function is known a manner as so-called back-turn gears, gear 142 serving to compensate the influence of

the rotation of shaft 38 which occurs when casing 14 is turned around axle 22 and which, owing to hollow shaft 141 not participating in the rotation, translates this to shaft 143. For this purpose spur-wheel 146 is rigidly connected to adjacent carrier 35. When shaft 38 begins to turn spur-wheel 147 rolls upon spur-wheel 146 and thus produces a rotary motion which superimposes itself on said rotary motion of shaft 143 in gear 142.

The result shaft of differential gear 145 carries spur-wheel 148 which engages spur-wheel 150 fixed on shaft 149. Shaft 149 rests rotatably in hollow shaft 44 and carries at its upper end gear 151 working together with rack 65. When disc wheel 45 is stationary any rotation of shaft 144 is directly translated to pair of spur-wheels 148, 150 and therewith to gear 151 and rack 65. In order to prevent rack 65 from shifting in respect of gear 151 any rotation of hollow shaft 44 is translated via bevel gears 46 and 152 to a second driving shaft of differential gear 145 and thus, via pair of spur-wheels 148, 150 and shaft 149, produces a rotation of gear 151 of such a magnitude that rack 65 is not shifted.

The aiming device described functions and works as follows: The operator of the gun seated on seat 6 (Fig. 1) follows the aircraft under fire with gun 3 by turning hand cranks 8 and 7 until, when looking through reflex sight 16, the aircraft is in the centre of the field of vision. If he now stops the gun the aircraft moves in a certain direction, the apparent target course away from the centre of the field of vision. Now the operator turns hand crank 59 (Fig. 2)—while gun 3 is still stationary—until the aircraft appears to move constantly between the two lines of the aiming point. As the aiming point and rack 65 are intergeared, the latter has thus been turned into a starting position in which it is parallel to the intersection line of said flying plane with a horizontal plane. In relation to a system of co-ordinates fixed in space the direction of this straight line remains the same as long as the aircraft moves in a straight line itself. Now the operator follows the aircraft again with his gun 3 by means of hand crank 7 and 8 (Fig. 1). He no longer sights it through the centre of his field of vision, but through the aiming point at a certain spot in the aiming line. In this manner, owing to the lateral aiming device of gun 3 being geared to rack 65 as described above, disc wheel 45 rotates constantly and automatically in such a manner that the rack always remains parallel to its starting position while the aiming line is turned in such a manner that it remains parallel to the flying plane.

An assistant operator sets at crank 125 the estimated or measured aircraft speed and at crank 112 the continuously altering distance of the target. In this way rack 65 is set at its right value and similarly cam 119 together with the superelevation angle resulting from the sighting of the target are properly set. Moreover, by setting rack 65 according to direction and length the position of the aiming point on the aiming line is determined, so that gun 3 is now in the position as regards both side angle and angle of sight corresponding to the time value. During firing operations the gun can either be made to follow the target by continuously turning hand cranks 7 and 8 (Fig. 1), or, if it is desired to lay a barrage, it can be stopped. In the latter case the aircraft will move away from the aiming point. In order to get the gun ready for another round the gunner need only sight the tar- 70

get again through the aiming mark. Direction and magnitude of the aiming-off distance are automatically adjusted.

The object of the present invention could in many respects be designed differently from this specific embodiment.

For instance, instead of the multiplication gear used, another gear, for example one working on the basis of logarithms, could be employed as described, for example, in the Netherlands Patent 28,615.

I claim:

1. In an aiming device, in combination with a gun, means for setting the gun laterally and in elevation, a reflex sight comprising a carrier, means rotatably supporting said carrier about an axis of said reflex sight, said axis serving as the direction for the projection of the center point of the reflex into the eye of an observer, 15 means constituting a straight directional line firmly mounted upon said carrier and extending through the axis of rotation thereof, optical means for projecting said straight line into the eye of the observer, means firmly connecting said 20 sight with the gun for transmitting the changes in the elevation of the gun to said sight, driving means for rotating said carrier, said driving means comprising a shaft, means maintaining said shaft vertical irrespective of the changes in 25 elevation of said sight, means connected with the first mentioned means and said shaft for transmitting each lateral rotation of the gun to said shaft in the form of a rotation of the same magnitude but of opposite direction, a manually 30 operable drive for rotating said shaft independently of said transmitted rotation thereof, another shaft extending parallel to the optical axis of the sight, a drive operatively connecting said carrier with the second mentioned shaft, and 35 means interconnecting said shafts for transmitting the rotation of the first mentioned shaft to the second mentioned shaft whereby said manual drive sets said directional line parallel to the apparent target direction.

2. In an aiming device, in combination with a gun, means for setting the gun laterally and in elevation, a reflex sight having a center point and comprising a carrier, means rotatably supporting said carrier about an axis of said reflex sight, said axis serving as the direction for the projection of the center point of the reflex into the eye of an observer, means constituting a straight directional line firmly mounted upon said carrier and extending through the axis of rotation 50 thereof, index means movably mounted upon said carrier and shiftable along said straight directional line, optical means for projecting said straight directional line and said index means into the eye of an observer, means connecting said sight with said gun for transmitting changes in elevation of said gun to said sight, driving means for rotating said carrier and for shifting said index means along said straight directional line, said driving means including a shaft, means maintaining said shaft vertical irrespective of changes in the elevation of said sight, a manual drive for said shaft, means independent of said manual drive and connected with the first mentioned means for causing a rotation of said shaft during each lateral rotation of the gun, the extent of rotation of said shaft being the same but taking place in the opposite direction, a member slidably mounted upon said shaft, said member being 55 slidable in a direction perpendicular to said shaft, a second shaft extending parallel to the

optical axis of said sight, means operatively connecting the second mentioned shaft with said carrier, a link, means including a joint connecting one end of said link with the second mentioned shaft to cause said link to rotate with the second mentioned shaft, the last-mentioned means causing said link to swing in relation to the axis of the second mentioned shaft, a universal joint connecting the opposite end of said link with said member, means transmitting the swinging movement of said link about the axis of the second mentioned shaft to said index means, and manually operated means for adjusting the distance of said universal joint from the axis of the first mentioned shaft, whereby said manual drive serves to adjust said directional line parallel to the apparent target direction and whereby said index means, the distance of which from the center point of said sight is adjustable by said manually operated means corresponding to the previously set aiming-off distance, serves for sighting the target.

3. In an aiming device, a reflex sight comprising a carrier, means rotatably supporting said carrier about an axis of said reflex sight, said axis serving as the direction for the projection of the center point of the reflex into the eye of an observer, means forming a straight directional line mounted upon said carrier and rotatable therewith, said straight directional line extending through the axis of rotation thereof, two rotatable rollers connected with said carrier, the centers of rotation of said rollers lying upon a straight line which is parallel to said directional line, a band extending over said rollers, index means, attached to said band between said rollers and movable along said directional line when said band moves over said rollers, a second carrier, means rotatably supporting said second carrier about an axis of rotation which is the same as that of the first mentioned carrier, the ends of said band being firmly connected with said second carrier, whereby said index means is shiftable along said directional line when the first mentioned carrier is rotated in relation to the second mentioned carrier, and optical means for projecting said directional line and said index means into the eye of an observer.

4. In an aiming device, in combination with a gun, means for setting the gun in train and elevation, a reflex sight comprising a carrier, means rotatably supporting said carrier about an optical axis of said reflex sight, means constituting a straight directional line rotatable together with said carrier, optical means for projecting said straight line into the eye of the observer, means connecting said sight with the gun for transmitting the training and elevating movements of the gun to the sight, a shaft, means maintaining said shaft vertical irrespective of the changes in elevation of said sight, means connected with the first-mentioned means and said shaft for transmitting training movements of the gun to said shaft in the form of a rotation of the same magnitude but of opposite direction to prevent a rotation of said shaft about its axis during training movements of the gun, another shaft extending in a vertical plane parallel to the gun axis, which shaft is adapted to participate in the elevating movement of the gun and is operatively connected with said carrier, means including an articulated joint connecting said shafts and a manually operable drive for rotating said carrier independently of the rotation transmitted to it, whereby the direction of said directional line

which is to be set initially by operating said manual drive is kept parallel to itself during training movements of the gun.

5. In an aiming device, in combination with a gun, means for setting the gun in train and elevation, a reflex sight comprising two carriers, means rotatably supporting the carriers about an optical axis of the reflex sight, means constituting a straight directional line rotatable together with a first one of said carriers, an index movably mounted upon said first carrier and shiftable along said straight directional line, means connecting the second-mentioned carrier with said index to cause the index to be shifted by a relative rotation of the second carrier with respect to the first carrier, optical means for projecting said directional line and said index into the eye of an observer, means connecting said sight with the gun for transmitting the training and elevating movements of the gun to the sight, a vertical shaft operatively connected with the first-mentioned means to transmit a rotation to the shaft about its axis equal to the training movement of the gun but of opposite direction, means connected with the shaft to be rotated with it and comprising an element movable in a radial direction with respect to the shaft, another shaft extending in a vertical plane parallel to the gun axis, which shaft is adapted to participate in the elevating movement of the gun and is operatively connected with the first-mentioned carrier, a link, the one end of which is articulately connected with said second-mentioned shaft to permit swinging movements of said link with respect to the second-mentioned shaft, and the other end of which is articulately connected with said element to transmit the rotations of the first-mentioned shaft to the second-mentioned shaft, a member adapted to rotate about the axis of the second-mentioned shaft and operatively connected with the second-mentioned carrier, to transmit its rotation to this carrier, means connected with the first-mentioned end of said link to transmit the rotation of the first-mentioned shaft to said member and to superimpose the swinging movement of said link to cause said index to be shifted along the directional line whenever a swinging movement of said link with respect to said second-mentioned shaft occurs.

6. In an aiming device, a reflex sight comprising a carrier, means rotatably supporting the carrier about an optical axis of the reflex sight, a screen which is transparent along a straight directional line and is connected with the carrier to be rotated with it, an index movably supported by the carrier to be shifted along said directional line, optical means to project both the directional line and the index along said optical axis into the eye of an observer.

7. In an aiming device, a reflex sight comprising two carriers, means rotatably supporting said carriers about an optical axis of said reflex sight, means forming a straight directional line rotatable together with one of said carriers, two rotatable rollers connected with the same carrier, a band supported by said rollers and extending between them along a straight line parallel to said directional line, the ends of the band being connected with the other carrier, an index attached to said band between said rollers and movable along said directional line when said band moves over said rollers, whereby said index is shiftable along said directional line, when said

13

two carriers are rotated with respect to each other.

ALFRED GERBER.
